COMBINED WHEEL AND DRIVE OR THE LIKE

Frank A. Glomb, Park Forest, and Victor Wasynczuk,
Chicago, Ill., assignors to Barnes & Reinecke, Inc.,
Chicago, Ill., a corporation of Delaware

Filed Apr. 28, 1961, Ser. No. 64,937

Term of patent 14 years

(Cl. D14—30)

Fig. 1.

Fig. 2.

Fig. 3.

FIG. 1 is a perspective view of a combined wheel and drive or the like showing our new design;

FIG. 2 is a front elevational view thereof; and

FIG. 3 is a sectional view taken substantially along the line 3-3 of FIG. 2.

The dominant features of our design are shown in full lines with the broken line illustration of the tire being omitted from FIGS. 2 and 3 for convenience of illustration.

We claim:
The ornamental design for a combined wheel and drive or the like, substantially as shown and described.
